UNITED STATES PATENT OFFICE.

RAY ZUG, OF LOS ANGELES, CALIFORNIA.

DESIGN FOR A COMBINED BRIDGE-LAMP BRACKET AND SMOKING SET.

Application filed October 6, 1925. Serial No. 15,031. Term of patent 14 years.

To all whom it may concern:

Be it known that I, RAY ZUG, a citizen of the United States, residing at Los Angeles, in the county of Los Angeles and State of California, have invented a new, original, and ornamental Design for Combined Bridge-Lamp Bracket and Smoking Set, of which the following is a specification, reference being had to the accompanying drawing, forming part thereof.

of my new design with the bridge table indicated in dotted outline.

Figure 2 is a plan of the bracket illustrated in Figure 1 and indicating the bridge table in dotted outline.

I claim:

The ornamental design for a combined bridge lamp bracket and smoking set as shown.

RAY ZUG.
